UNITED STATES PATENT OFFICE.

LLOYD A. HAMMARLUND, OF NEW YORK, N. Y., ASSIGNOR TO AUTOMOBILE CLOCK COMPANY, INC., OF NEW YORK, N. Y., A CORPORATION OF DELAWARE.

CLOCK.

Application filed March 25, 1922. Serial No. 546,750.

To all whom it may concern:

Be it known that I, LLOYD A. HAMMARLUND, a citizen of the United States, and resident of the borough of Manhattan, in the city and State of New York, have invented a new and useful Improvement in Clocks, of which the following is a specification.

The object of my invention is to provide certain improvements in the construction, form and arrangement of the several parts of a clock and especially a clock designed for use in connection with automobiles, air-ships, boats, etc., where the clock is subjected to more or less exposure, to rough usage and to theft.

My improved clock more particularly includes a fixed outer casing and a rotatable and extensible inner casing located within the outer casing, means being provided whereby the clock spring may be wound, the hands may be set and the clock dial properly positioned, by rotary movements of the inner casing.

A practical embodiment of my invention is represented in the accompanying drawings, in which

Fig. 1 represents the clock partly in side elevation and partly in section, attached to a suitable support.

Fig. 2 represents a section on the line II—II, looking in the direction of the arrows.

Fig. 3 represents a section taken in the plane of the line III—III, looking in the direction of the arrows.

Fig. 4 represents a back view of the clock, a portion of the back of the outer casing being broken away.

Fig. 5 represents a front view of the clock.

Fig. 6 represents a face view of the inner casing front plate and clock movement frame.

Fig. 7 represents a side view of the same.

Fig. 8 represents a back view of the same.

Fig. 9 represents a detail section taken in the plane of the line IX—IX of Fig. 1, looking in the direction of the arrows.

Fig. 10 represents a section taken in the plane of the line X—X of Fig. 9, looking in the direction of the arrows.

The outer cylindrical casing 1 is closed at its back end and open at its front end. This outer casing is provided with a peripheral external lateral flange 2, provided with holes 3 for the reception of fastening screws 4, to

fixedly secure the outer casing to an instrument board or other suitable support 5. The closed back end of this outer casing 1 is provided with a centrally arranged hole 7, the purpose of which will be hereinafter described.

The inner cylindrical casing 8 has a rotary and sliding fit within the outer casing 1, the rear end of the inner casing being closed. The front end of the inner casing 65 is provided with and closed by a front plate 12, having a forwardly extended peripheral flange 13. The heads of the screws 4 are located in the space between the flange 2 of the outer casing and the front plate 12 of the 70 inner casing. This front plate is provided with rearwardly offset lugs 14, by means of which the front plate is secured to the clock movement frame 15, through screws 16, which screws serve to draw the open front 75 end of the inner casing 8 snugly into engagement with the front plate, it being noted that the rear end of the inner casing 8 is secured to the rear plate 17 of the clock movement frame by the screws 18. 80

A rim 19 is provided with an inwardly extended flange 20 which fits over the flange 13 of the front plate, which serves to hold the unit 21 in position. Screws 22 engaging the rim 19 and flange 13, serve to secure the 85 rim to the front plate. Between the window 21 and the front plate 12 I locate a combined dial 23 and reflector ring 24, preferably made integral, the offset securing lugs 14 struck rearwardly from the front plate 90 12, serving to permit the dial to be secured against the front face of the front plate by the fastening screws 25. The usual hands 26 are located within the space between the dial and window, and are mounted as usual 95 on the arbors 27, 28.

I have omitted practically all of the clock movement except the clock spring 29, which clock spring is provided with a tubular arbor 30 which projects through the rear end of 100 the inner casing 8 and is screwed into the rotary member 31 of a clutch, which is located within the cup-shaped stationary member 32, secured by the screws 33 to the back end of the outer casing 1. Clutch rollers 34 105 serve to clutch the rotary member 31 to the fixed member 32 of the clutch, when the inner casing is rotated in one direction for winding the clock spring.

A spring 35 is interposed between the 110

front face of the rotary clutch member and the back face of the fixed clutch member, which ring serves to hold the rotatable and extensible inner casing normally in its unextended or retracted position.

The hand arbor 27 is provided with an extension 36, located within the tubular clock spring arbor 30 and projecting rearwardly through the hole 7 in the back end 19 of the outer casing 1, where the said extension is provided with a portion 37 which is arranged to be brought into interlocking engagement with the walls of the hole 7 when the inner casing is extended, so that 15 the clock hands may be set by the rotary movement of the inner casing in one direction, while extended.

The clock dial may be properly positioned by a rotary movement of the inner casing, 20 while in its unextended position, said movement being opposite to the movement of the inner casing when the clock spring is being wound, it being understood that the slipping of the clutch connection between the fixed 25 outer casing and clock spring arbor, permits of this movement.

I have provided means for yieldingly holding the inner casing in its adjusted position, which means in the present instance 30 is shown as comprising a spring catch 38, secured to the front face of the fixed clutch member 32, the ends 39 of which catch is adapted to enter a recess 40 in the rear end of the inner casing 8.

35 A pawl and ratchet connection 41, 42, is provided between the geared wheel 43 of the clock movement and the tubular clock spring arbor 30, a spring 44 being provided for holding the pawl 41 in engagement with 40 the ratchet 42.

It is evident that various changes may be resorted to in the construction, form and arrangement of the several parts without departing from the spirit and scope of my 45 invention; hence, I do not wish to limit myself to the particular embodiment herein shown and described, but

What I claim is:

1. In a clock, a fixed outer casing, a rotatable inner casing carrying the clock movement, and means for setting the clock hands by a rotary movement of the inner casing.

2. In a clock, a fixed outer casing, a rotatable inner casing carrying the clock movement, and means for winding the clock movement by a rotary movement of the inner casing.

3. In a clock, a fixed outer casing, a rotatable inner casing carrying the clock movement, and means for setting the clock hands and winding the clock movement by rotary movements of the inner casing.

4. In a clock, a fixed outer casing, a rotatable inner casing carrying the clock

movement, manual means for positioning the clock dial by a rotary movement of the inner casing, and means for yieldingly holding the inner casing in its adjusted position.

5. In a clock, a fixed outer casing, a rotatable inner casing carrying the clock movement, manual means for setting the clock hands and for positioning the clock dial by rotary movements of the inner casing, and means for yieldingly holding the inner casing in its adjusted position. 70

6. In a clock, a fixed outer casing, a rotatable inner casing carrying the clock movement, manual means for winding the clock movement and for positioning the clock dial by rotary movements of the inner casing, and means for yieldingly holding the inner casing in its adjusted position. 80

7. In a clock, a fixed outer casing, a rotatable inner casing carrying the clock movements, manual means for setting the clock hands, for winding the clock movement and for positioning the clock dial by rotary movements of the inner casing, and means for yieldingly holding the inner casing in its adjusted position. 90

8. In a clock, a fixed outer casing, a rotatable and extensible inner casing carrying the clock movement, and means for setting the clock hands by a rotary movement of the inner casing, while extended. 95

9. In a clock, a fixed outer casing, a rotatable and extensible inner casing carrying the clock movement, and means for winding the clock movement by a rotary movement of the inner casing, while unextended. 100

10. In a clock, a fixed outer casing, a rotatable and extensible inner casing carrying the clock movement, manual means for positioning the clock dial by a rotary movement of the inner casing, while unextended, and means for yieldingly holding the inner casing in its adjusted position. 105

11. In a clock, a fixed outer casing, a rotatable and extensible inner casing carrying the clock movement, and means for setting the clock hands by a rotary movement of the inner casing in one direction, while extended, and for winding the clock movement by a rotary movement of the inner casing in the opposite direction, while unextended. 110

12. In a clock, a fixed outer casing, a rotatable and extensible inner casing carrying the clock movement, means for setting the clock hands by a rotary movement of the inner casing in one direction, while extended, manual means for positioning the clock dial by a rotary movement of the inner casing in the same direction, while unextended, and means for yieldingly holding the inner casing in its adjusted position. 115

13. In a clock, a fixed outer casing, a rotatable and extensible inner casing carrying the clock movement, means for winding the

clock movement by a rotary movement of the inner casing in one direction, while unextended, manual means for positioning the clock dial by a rotary movement of the inner casing in the opposite direction, while unextended, and means for yieldingly holding the inner casing in its adjusted position.

14. In a clock, a fixed outer casing, a rotatable and extensible inner casing carrying the clock movement, means for setting the clock hands by a rotary movement of the inner casing in one direction, while extended, means for winding the clock movement by a rotary movement of the inner casing in the opposite direction, while unextended, manual means for positioning the clock dial by a rotary movement of the inner casing in the first named direction, while unextended, and means for yieldingly holding the inner casing in its adjusted position.

15. In a clock, a fixed outer casing, a rotatable and extensible inner casing carrying the clock movement, and hand controlling means carried by the inner casing, arranged to be interlocked with the outer casing by the extension of the inner casing, whereby the rotary movement of the inner casing, while extended, will set the hands.

16. In a clock, a fixed outer casing, a rotatable and extensible inner casing carrying the clock movement, the back of the outer casing having a hole therethrough, and a hand controlling arbor projecting through the hole and having a portion arranged to be moved into interlocking engagement with the walls of the hole by the extension of the inner casing whereby the rotary movement of the inner casing, while extended, will set the hands.

17. In a clock, a fixed outer casing, a rotatable and extensible inner casing carrying the clock movement, manual means for posi-

tioning the clock dial by a rotary movement of the inner casing, while unextended, and coacting means between the inner and outer casings arranged to yieldingly hold the inner casing in its adjusted position.

18. In a clock, a fixed outer casing, a rotatable and extensible inner casing carrying the clock movement, means for positioning the clock dial by a rotary movement of the inner casing, while unextended, a spring catch carried by the outer casing, and a recess in the inner casing adapted to receive the catch for yieldingly holding the inner casing in its adjusted position.

19. In a clock, a fixed outer casing, a rotatable and extensible inner casing carrying the clock movement, and a clutch connection between the outer casing and clock spring winding arbor, whereby the clock spring is wound by a rotary movement of the inner member.

20. In a clock, a fixed outer casing, a rotatable and extensible inner casing carrying the clock movement, a fixed clutch member carried by the outer casing, a rotary clutch member carried by the clock spring winding arbor, and an interposed clutch roller operative to cause the rotary movement of the inner casing to wind the clock spring.

21. In a clock, a fixed outer casing, an inner casing carrying the clock movement, a front plate having rearwardly offset lugs secured to the clock movement to cover the open front of the inner casing, a combined dial and reflector ring secured to the face of the front plate, said front plate having a forwardly extended peripheral flange, a window, and a rim engaging said flange for securing the window to the front plate.

In testimony, that I claim the foregoing as my invention, I have signed my name this 21st day of March 1922.

LLOYD A. HAMMARLUND.
